ELECTRIC DISCHARGE TUBE

Nicolaas Warmoltz, Eindhoven, Netherlands, assignor to Hartford National Bank and Trust Company, Hartford, Conn., as trustee

Application February 12, 1947, Serial No. 728,108
In the Netherlands July 29, 1944

Section 1, Public Law 690, August 8, 1946
Patent expires July 29, 1964

1 Claim. (Cl. 250—27.5)

1

This invention relates to an electric discharge tube comprising a liquid or a solid cathode and an ignition electrode constituted by a non-insulating member surrounded by insulating material which is, in part, contained in the cathode. The non-insulating material may be a conductor or a semi-conductor; furthermore the insulator may contain a gas which breaks down at a high voltage.

In tubes provided with the aforesaid ignition electrodes the ignition is set up by a spark produced in the narrow slit between the ignition electrode and the cathode surface, which in the case of a liquid cathode is generated owing to the capillary depression, on a high, generally positive voltage being placed on the conductor. This is the reason why these ignition electrodes are referred to as spark strikers.

Generally speaking, tubes comprising spark strikers operate satisfactorily, but only for a short time. Generally, a thin layer of precipitate is formed on the outside of the ignition electrode and this layer prevents a spark initiating the ignition from being produced. The breakdown of the striker may be remedied by raising the ignition voltage, but generally only for a short time.

In an electric discharge tube according to the invention, comprising a liquid or a solid cathode and an ignition electrode constituted by a non-insulating member surrounded by insulating material which is, in part, enclosed in the cathode, the ignition electrode above the cathode surface down to a short distance therefrom is coated with a non-insulating layer. The distance between the cathode surface and the non-insulating layer on the ignition electrode ranges from a few millimeters to a few centimeters in accordance with the variations of the cathode level and the voltage applied to the ignition electrode, and also with the height up to which the ignition electrode in tubes of the type concerned is covered with a layer of precipitate. The non-insulating layer mounted on the striker may have a very heavy resistance and hence also semiconductors may be used. The non-insulating layer must be mounted so as to make contact with the precipitate formed. According to the invention it has been found that tubes provided with an ignition electrode according to the invention act reliably for a long time; the satisfactory operation may be due to the layer of dirt formed on the ignition electrode being burnt off by the supply current passing through or by jump-over sparks before this layer can affect

2

the ignition, since this does not occur in the case of minute thickness. As an alternative, it may be that the layer of dirt jointly with the conductive layer on the ignition electrode starts to act as a resistance striker, with the result that the ignition electrode keeps on playing its part nevertheless; the layer of dirt may in this case be burnt away nevertheless.

It has been suggested before to make ignition electrodes constituted by a stud of insulating material partly immersed in the cathode liquid and coated down, to a few centimeters' distance from the cathode surface with a metal layer. The insulating stud contains a conductor which is not connected to the supply wire for the ignition electrode, but which may be connected to the cathode. In this case the ignition is set up by jump-over sparks along the surface of the insulating stud.

Spark strikers are known in which the supply wire of the spark striker inside the tube is not coated with insulating material and is deformed to form an auxiliary anode for the improvement of the ignition. This uncoated supply wire is, however, spaced away too far from the cathode surface to be able to accomplish the same function as the conductive layer of the ignition electrode according to the invention.

In order that the invention may be clearly understood and readily carried into effect, it will now be set out more fully with reference to the accompanying drawing, which illustrates an electric discharge tube comprising an ignition electrode according to the invention.

Referring to the single figure of the drawing, 1 designates the wall of the discharge tube inside of which are enclosed the cathode 2 of mercury and the anode 3 of carbon. The ignition electrode is constituted by a quartz tube 5 which is partly filled with a supply of mercury 6 which makes contact with a supply wire 4. The top of the ignition electrode is coated with a thin layer of nickel 7 which is also connected with the supply wire 4. The quartz tube 5 has a wall thickness of 0.5 mm.; the ignition voltage has a value of about 8000 volts. Thanks to the application of the conductive layer 7 the tube operates reliably for a considerably longer period than would be the case without this layer being provided on the striker, for example two or three times as long.

What I claim is:

An electric discharge tube having a liquid cathode and an ignition electrode constituted by a conducting member surrounded by insulating ma-

terial which is, in part, immersed in the cathode, and the part of the ignition electrode that is out of the cathode being coated to a short distance from the cathode surface with a non-insulating layer which is conductively connected to the conductor of the striker.
